UNITED STATES PATENT OFFICE.

FRED LACEY, OF VALLEYFIELD, CANADA.

HARNESS-OPERATING MECHANISM FOR LOOMS.

SPECIFICATION forming part of Letters Patent No. 650,813, dated May 29, 1900.

Application filed October 14, 1899. Serial No. 733,552. (No model.)

To all whom it may concern:

Be it known that I, FRED LACEY, a citizen of the United States, residing at Valleyfield, in the county of Beauharnois, Province of Quebec, Dominion of Canada, have invented a certain new and useful Improvement in Harness-Operating Mechanism for Looms, of which the following is a specification, reference being had therein to the accompanying drawings.

In looms for performing certain kinds of weaving the movements of the harness-frames for producing the successive sheds among the warp-threads are derived, primarily, from positively-acting devices provided for the purpose, which devices may comprise, for instance, cams acting upon levers or treadles that are connected with the harness-frames. The harness-frames also have connected therewith arrangements of cording, &c., whereby when movement in one direction is communicated to the predetermined harness-frame or harness-frames by the action of the devices first mentioned the harness-frame or harness-frames requiring to be moved in the reverse direction will be shifted in that direction, and whereby, also, the harness-frames which do not require to be shifted will be held in their proper position. The present invention has relation to arrangements of the class last mentioned.

In reducing the invention to practice I employ in a loom a series of movable arms or carriers, which latter are operatively connected with the series of harness-frames in such loom, so that the respective arms or carriers move in unison with particular harness-frames. Each of the said movable arms or carriers has applied thereto a sheave or equivalent guide for a flexible connector. A second series of sheaves or equivalent guides is arranged adjacent to the said arms or carriers. A continuous cord, chain, or the like flexible connector is applied to the two series of sheaves or guides, passing alternately around a sheave or guide on one of the arms or carriers, then around one of the sheaves or guides of the other series aforesaid, then around another sheave or guide on an adjoining arm or carrier, and so on throughout the two series of sheaves or guides. Hereinafter for convenience in description the terms

"sheave" and "cord" alone are used in some instances; but it will be understood that I do not restrict myself specifically thereto. 55 Each sheave or guide carried by one of the arms or carriers is received within a loop or bight of the said continuous cord or flexible connector extending from sheaves or guides of the opposing series. When a given harness-frame is moved in one direction by the action of the corresponding cam upon the lever or treadle which is connected with such harness-frame or other operating mechanism, the movement of the arm or carrier that also 60 is in connection with such harness-frame causes a lengthening out or extension of the loop or bight that passes around the sheave or guide that is carried by such arm. This operates in obvious manner with a tendency 65 to shorten the other loops or bights in said cord and to draw in the reverse direction any harness-frame which is free to be thus drawn, in addition to maintaining the remaining harness-frames stationary in their normal position. 70

Various modifications are possible within the limits of my invention in the construction and arrangement of the features of the invention and in the manner of applying and 75 using the said features. In the accompanying drawings I have illustrated certain of these modifications.

Having reference to the drawings, Figure 1 is a view showing in front elevation one embodiment of my invention, and one mode of making application of the invention, portions of a loom-arch and of two harness-frames being represented. Fig. 2 shows in plan the parts in Fig. 1 which are more immediately involved in 80 the invention. Fig. 3 is a view in vertical section on the plane indicated by the dotted line 3-3 in Fig. 2 looking in the direction indicated by the arrows near the ends of such line. Fig. 4 is a view showing in front elevation 85 another embodiment of the invention and another mode of applying the same in practice. Fig. 5 is a partial plan of the parts in Fig. 4. Fig. 6 is a front elevation illustrating a further modification of the invention. 90 Fig. 7 is a partial plan of the parts in Fig. 6. Fig. 8 is a view on the order of a diagram 95 illustrating a further modification of the invention. 100

In the drawings, referring first to Figs. 1, 2, and 3, 1 designates part of the arch of a loom-frame. 2 2 designate harness-frames. 3 3 designate straps, with the lower ends of 5 which are connected the wire connections 4 4, the ends of the latter being attached to the harness-frames. 5 5 are the movable arms or carriers. The arms shown in the drawings are provided with segmental ends 51 51, to 10 which are attached the straps 3 3, and they are mounted pivotally upon a rod 6, the latter being carried by a stand 7, which is applied to the loom-arch 1. The harness-frames 2 2 are suspended from the segmental ends 15 51 51 of arms 5 5 by means of the said straps 3 3 and wire connections 4 4. The arms 5 5 are confined between stand 7 and a plate 8. One end of plate 8 is fitted upon the said bolt 6, nuts 61 61 being applied to the opposite 20 ends of such bolt for the purpose of holding the stand 7, arms 5 5, and plate 8 together at the pivotal ends of the arms. A tie-rod 9 passes through holes in the stand 7 and plate 8 and through segmental slots 52 52 in the 25 arms 5 5, it receiving nuts 91 91 upon its opposite ends and serving to hold the parts together at an intermediate point in the length of the arms. The portions of the arms in which the slots 52 52 are formed constitute 30 lateral extensions, which by their mutual contact serve to guide and steady the arms in their movement. These latter functions are shared also by the segments 51 51. 10 designates the sheave which is applied to each 35 arm or carrier 5. Herein each sheave 10 is mounted upon a pin 53, with which the corresponding arm or carrier is provided, the said pin projecting laterally from the arm or carrier, although the precise manner and 40 means of mounting the sheave upon the arm or carrier are not essential to the invention, the requisite being that the sheave shall be positioned by the arm or carrier in the working of the parts. The second series of sheaves 45 is shown at 11 11. The sheaves 11 11 are mounted upon a rod 12, which is supported in the upper portions of the stand 7 and plate 8. 13 designates the cord which is applied to the sheaves 10 and 11, it proceeding, as shown, 50 alternately partially around a sheave 11, then partially around a sheave 10, then partially around a sheave 11, and so on. As will be perceived, the sheaves 10 10 are received within loops or bights of the cord 13, extending 55 from sheaves 11 11. From the first and last sheaves 10 10 in Figs. 1, 2, and 3 the cord 13 extends through guides 14 14 and partly around guide-sheaves 15 15, which last are mounted to rotate on pins 16 16, carried by 60 the supporting-bracket 17, which herein is shown as having its depending arms applied to the opposite ends of rod 12 and secured in position thereon by the clamping-screws 18 18. 65 In practice when one of the harness-frames 2 2 is depressed by the action of its cam or other actuator (not necessary to be shown)

the corresponding arm or carrier 5 is moved in a corresponding direction through the described connections. This extends the loop 70 or bight of cord 13, which contains the sheave 10 or other guide of the arm or carrier. As such loop or bight extends or lengthens the tendency is to shorten the other loops or bights, drawing up any one thereof corresponding with a harness-frame which has been moved into its depressed position and is now free to rise and operate to hold the various harness-frames in their normal elevated positions, with the exception of the one 80 which has been depressed, as explained.

In the arrangement shown in Figs. 1, 2, and 3 the cord 13 is endless, and when more than four harness-frames are employed it usually is left free to shift back and forth over the 85 guide-sheaves 15 15 in the working of the mechanism. This shifts the wear resulting from the working of the arms 5 5. It also facilitates the working of the arms at opposite 90 ends of the series, since when such arms succeed each other in being drawn down the necessary slack in the cord will be obtained, in whole or in part, in consequence of movement of the upper portion of the cord over the said guide-sheaves. Thereby friction and wear 95 due to movement of the cord around a good many sheaves or guides is avoided.

The mechanism shown in Figs. 1, 2, and 3 is designed more especially for use in cases in which more than four harness-frames are 100 operated. When the mechanism is used in connection with four harness-frames, the cord 13 does not need to be endless, and its ends may be fixed in the two guides 14 14, as by means of clamping-screws 19 19, applied to 105 the said guides and compressing the cord within the same. In this case the guide-sheaves 15 15 may be omitted.

Figs. 1, 2, and 3 show the improved mechanism, located near the middle of the loom-arch, with the arms 5 5, to which the harness-frames are connected, in a horizontal position, their segmental inner ends 51 51 being over the middle of the lengths of the harness-frames. In these figures the sheaves 11 11 115 are above the sheaves 10 10, which are mounted on the said arms or carriers. The location and arrangement of the mechanism in the loom may be varied according to circumstances in practice. 120

Figs. 4 and 5 show a modification of the invention in which the arms or carriers 5 5 are disposed in a vertical position at one end of the loom, their segmental ends 51 51 here being uppermost and arranged to move outwardly and inwardly, while the sheaves 11 are at one side of the sheaves 10, carried by the said arms and outside the latter. The harness connections 41 41 here pass partially around direction-changing sheaves 21 21 on 130 the loom-arch on their way from the harness-frames to the arms 5 5. In these figures last mentioned by way of illustrating the use of the invention in connection with five harness-

frames or less the ends of cord 13 are represented as attached to fixed parts—as, for instance, to screws, pins, or other projections, as 20 20, on the stand 7 and plate 8.

- 5 In the modifications which have thus far been referred to the harness connections have extended directly to the carriers for the movably-mounted sheaves 10 10. Figs. 6 and 7 show a modification in which the harness 10 connections, here designated 42 42, from successive harness-frames are joined to straps 3 3, that are connected with the segmental ends 54 54 of arms 55 55, which are mounted pivotally at 56 56 and which in turn are operatively connected with movable carriers 57 for the sheaves 10. The operative connection between each arm 55 and the corresponding carrier 57 may be effected variously in practice. Herein a pin 58 on one of the said parts 20 is shown working in a hole in the other thereof. The hole at one end of the carrier is made in the form of a longitudinal slot to permit the corresponding pin 58 to play freely therein as the arms and carrier vibrate up 25 and down. In Figs. 6 and 7 each carrier 57 is connected at one end thereof with an arm 55 pertaining to one harness-frame and at the end thereof with the like arm pertaining to the next adjacent harness-frame. This reduces by one-half the number of sheaves 30 which are necessary to be employed and also lessens the friction due to the working of the parts and the resulting wear. The arms 55 55 are pivoted alternately above and below. 35 The pivots of the sheaves 10 10 preferably are located at different distances from the pivotal rod 6 for the arms or carriers 55, being arranged progressively nearer said rod in proceeding from front to rear in the loom. 40 This enables the rear harness-frames to be moved proportionately farther in shedding in order to produce clear V-sheds. The same result in the shedding may be attained by varying the distance from the pivotal support 45 of the arms at which the harness-frames are connected with the arms. The sheaves 11 11 preferably stand in an oblique or angular position with relation to sheaves 10 10, as indicated most clearly in Fig. 2. Each sheave 50 11 supports a cord 13 on its way from one sheave 10 to another next adjoining, and this oblique or angular position of the former enables the cord to pass readily to and from sheave 11 without rubbing and friction, without wear resulting therefrom, and without 55 tendency to slip off from the different sheaves. When the number of harness-frames in use at any time in a loom having applied thereto a mechanism or attachment embodying my 60 invention is less than the full number for which the latter has been designed, the arms or carriers which are not required to be utilized will be locked in an inoperative position, as by the use of blocks inserted into the slots 65 52 or by means of pins crossing such slots, the said blocks or pins engaging with the rod 12 to hold the arms or carriers immovable.

When a considerable number of harness-frames is in use in a loom, two or more of the flexible connectors may be utilized, each in connection with a different part of the entire series of harness-frames. Thus Fig. 8 shows an arrangement which is intended for use with eight harness-frames. In said figure the top shafts of such harness-frames are indicated and designated *a* to *h*, and two flexible connectors are represented, one being employed for the harness-frames which are numbered from *a* to *d*, while the other is employed for the harness-frames which are numbered from *e* to *h*. Each of such flexible connectors is shown as endless and as passing over a guide-sheave 151. With this arrangement there is much less wear on the respective connectors than there would be upon a single connector used with a similar number of harness-frames. The two guide-sheaves 151 151 may be mounted upon opposite arms of a supporting-lever 152, which latter turns more or less on its pivot to accommodate the extent of movement of the respective harness-frames during the working of the loom.

I claim as my invention—

1. In harness - operating mechanism for looms, in combination, the independently-movable carriers for connection with the respective harness-frames, the sheaves or guides carried and positioned by the said carriers, the second series of sheaves or guides, and the flexible connector passing around sheaves or guides in the two series alternately. 95
2. In harness - operating mechanism for looms, in combination, the pivoted arms or carriers for connection with the respective harness-frames, the sheaves or guides carried by the said arms or carriers at varying distances from the pivotal points thereof, the second series of sheaves or guides, and the cord passing around sheaves or guides in the two series alternately. 105
3. In harness - operating mechanism for looms, in combination, the independently-movable carriers for connection with the respective harness-frames, the sheaves or guides carried and positioned by the said carriers, the second series of obliquely - disposed sheaves or guides and the flexible connector passing around sheaves or guides in the two series alternately. 115
4. In harness - operating mechanism for looms, in combination, the pivoted arms or carriers for connection with the respective harness-frames, the sheaves or guides carried by the said arms or carriers at varying distances from the pivotal points thereof, the second series of obliquely-disposed sheaves or guides and the flexible connector passing around sheaves or guides in the two series alternately. 120
5. In harness - operating mechanism for looms, in combination, the independently-movable carriers for connection with the respective harness-frames, the sheaves or guides carried and positioned by the said carriers, 130

the second series of sheaves or guides, the endless flexible connector passing around sheaves or guides in the two series alternately, and means to guide the said flexible connector in completing its circuit.

5 6. In harness - operating mechanism for looms, in combination, the independently-movable carriers for connection with the respective harness-frames, the sheaves or guides
10 carried and positioned by the said carriers, the second series of sheaves or guides, the

endless flexible connector passing around sheaves or guides in the two series alternately, and one or more sheaves to guide the said flexible connector in completing its circuit.

15 In testimony whereof I affix my signature in presence of two witnesses.

FRED LACEY.
